UNITED STATES PATENT OFFICE.

RICHARD NAGEL, OF SPANDAU, GERMANY, ASSIGNOR TO F. AUGUST SCHROEDER, OF NEW YORK, N. Y.

ELECTROSTATIC TELEPHONE.

Application filed May 9, 1928, Serial No. 276,490, and in Germany April 28, 1926.

My invention relates to an electrostatic telephone and more particularly to a telephone of the stated type, the objects of which include the obtaining of high efficiency and 5 reliability of operation, with a construction which is highly practical and which may be manufactured at a comparatively low cost.

Electrostatic telephones as hitherto constructed are provided, in order to comply 10 with the above stated requirements, with strong, solid capacity bodies, such as castings which are worked and finished by means of special turning, grinding and polishing machines. Telephones or loud speakers constructed in this way necessarily have considerable weight and, therefore, cause inconvenience in moving them from place to place.

One object of my invention is to remedy this defect and with this object in view I provide, with the particular example of the invention here shown, in lieu of the heavy undivided capacity body hitherto used, a composite body, made of sheet metal and composed of a plurality of individual units or 25 members interconnected to form in their totality a rigid body of the required shape and with an absolutely plain operating surface. The means I employ for the interconnecting purpose may be of various kinds 30 such as clinchers, brackets, rings or similar fixtures.

In a preferred construction I employ sheet metal members or units of segmental shape which are to be interconnected only at their 35 peripheral and central ends, while the radial edges thereof remain unconnected. Preferably I use for the purpose segmental sheets of a light metal or alloy of a thickness of approximately 1 millimetre and I provide perforations therein in the manner of a sieve. For reinforcing purposes I bend the free 40 radial edges of the segmental members so that they form flanges projecting from the rear surface or side thereof, that is to say, the 45 surface turned away from the diaphragm, and constituting a reliable reinforcing means.

A construction adapted to be used in combination with the capacity body hereinbefore described, in general may comprise a wheel-like body made of a light metal or alloy, and 50 a preferably metallic thin sheet or foil which is kept under tension while being placed upon the said wheel-like body in order to be firmly connected therewith. In one example

of the invention an insulating ring corresponding to the rim of the mentioned wheel-like body, as regards circumferential size, is employed to overlie the diaphragm and the segmental members are placed upon such insulating ring so as to be supported peripherally by the rim portion of the wheel-like body and centrally by the hub portion thereof, with the insulating ring intermediate between the rim portion of the wheel-like body and the peripheral ends of the segmental 60 members, and with an insulating disk between the hub portion of the same and the central ends of the segmental members, so that the assembled parts will be properly insulated. 70

All of the segmental members having been accurately assembled to form a closed circular grid on the wheel-like body, an annular insulating body of comparatively great thickness is to be placed over and upon the peripheral ends of the segmental members. The annular body is similar to the rim of the wheel-like body, in diametrical respects, and both bodies are provided with registering holes for the reception of screws for firmly 80 uniting the two bodies with the capacity grid and the diaphragm inclusive of the insulating means therebetween, the diaphragm thus being safely held in place to maintain the full of its tension previously imparted to it. 85

The segmental members constituting the capacity body preferably may be of the same size and shape. It goes without saying, however, as to certain phases of the invention that they may be made of different areas and given any different sizes as regards the angle 90 formed by the two radial edges of each member, and the capacity body may be composed of any desired number of segmental members of the same size or of different sizes. 95

With the above recited objects and general purposes in view, the invention resides in the novel features of construction and combinations of parts as set forth in the following specification, as particularly pointed out in the appended claims and illustrated in the accompanying drawings, it being understood that the right is reserved to embodiments other than those actually illustrated herein, to the full extent indicated by the general meaning of the terms in which the claims are expressed. 100

In the accompanying drawings, forming

a part of this specification, and showing for exemplification a preferred form and manner in which the invention may be embodied and practices, but without limiting the 5 claimed invention to such illustrative instance:

Figure 1 is a top view of one half of the wheel-like body for use in connection with an electrostatic telephone having a capacity 10 surface or grid-plate composed of a number of segmental members of like shape and size; Figure 2 is a similar view of the same with all of the parts constituting the telephone 15 duly assembled, but partially broken away 15 to expose underlying parts; Figure 3 is a sectional view, the section being taken on the line A—B of Figure 1;

Figure 4 is a perspective view of one of the segmental members; Figure 5 is a sectional view with the section taken on the line C—D of Figure 4; and Figure 6 is a perspective view of one of the segments constituting the annular insulating body.

Parts which are repeated in the several 25 figures bear the same reference characters in each case.

Referring to Figure 1 the wheel-like body 10 preferably made of a suitable aluminium alloy, comprises a rim 11, spokes 12 and a 30 hub 13 having a threaded central bore 14 for the reception of a screw. The thin metallic sheet or foil constituting the diaphragm 15 is supported by the wheel 10 and affixed thereto while being kept under suitable 35 tension.

The segmental members 16 to be mounted over and upon the diaphragm 15 in parallel relationship thereto, are made of a suitable sheet metal such as an aluminium alloy, and 40 are provided throughout the whole area between the turned-up radial edges or flanges 18 with small holes or perforations 17 of circular or any other appropriate form, while the peripheral ends 19 and the central ends 45 20 of the segmental members 16 are preferably not perforated, as will be seen in Figure 4.

The area 19 forming the larger peripheral end of each segmental member 16 may be 50 provided with two holes 21 and 22, a lateral nose or lug 24 on one side and a correspondingly shaped recess 23 on the other side for the reception of the lug of the adjacent member when the members are duly assembled to 55 form a circular body. In this way the assemblage of the members 16 to constitute the latter may be effected in a ready manner and any unintentional displacement of the members with relation to each other during 60 the assembling and mounting operations is prevented.

Inserted between the wheel 10 and the segmental members 16 is an insulating sheet or membrane 25 which has two holes 26 cor- 65 responding, as regards location to the holes

21 and 22 of the area 19. Instead of a membrane such as 25, any other insulating members or even an insulating ring of appropriate shape and size to conform to the rim 11 of the wheel, may be employed. 70

The smaller central ends 20 of the segmental members 16 are supported by the hub 13 of the wheel 10 and a suitable insulating member may likewise be interposed between the ends 20 and the hub 13. This insulating 75 member may be the sheet or membrane 25 or else a separate insulating means such as a small disk or the like or both may be used for the purpose in view.

When the parts so far described are properly assembled, they are to be interconnected in the following manner in order to constitute a rigidly framed structure. I place a rubber ring or washer 27 on the central part of the capacity grid so that the ends 20 of the segmental members 16 will lie between the washer 27 and the hub 13 of the wheel 10, as clearly shown in Figure 3, and on top of the washer 27 I place a metallic disk 28 having a central bore for the accommodation of a screw 29, whereupon I firmly connect the disk 28 with the hub 13 by means of the screw 29 engaging in the threaded bore 14 of the hub. 90

When the parts thus have been rigidly connected at the centre of the telephone I proceed to firmly unite the same at the periphery by mounting an annular body of insulating material on the rim 11 of the wheel with the parts 16, 25 and 16 lying between the wheel 100 and the said annular body. Preferably I employ for the purpose a hard rubber body subdivided into segments 30 with bores 31 for the reception of screws 32. The latter pass through the holes 21, 22 and 26 of the segmental members and the insulating ring or sheet 25, respectively, and engage in threaded bores of the rim 11, as will be readily seen in Figure 3. 105

What I claim is:—

1. An electrostatic telephone, comprising a diaphragm, a capacity body composed of a plurality of members of sheet metal, and means for assembling and interconnecting the said members to form a rigid structure. 110

2. An electrostatic telephone, comprising a diaphragm, a capacity body composed of segmental members of sheet metal arranged radially close by each other, and means for interconnecting the said members to form a 120 rigid structure.

3. An electrostatic telephone, comprising a diaphragm, a capacity body composed of segmental members of sheet metal arranged radially close to each other, and means for interconnecting the central smaller ends and the peripheral larger ends, respectively, with each other. 125

4. An electrostatic telephone, comprising a diaphragm, a capacity body composed of 130

- segmental members having lateral or radial flanges and assembled with their flanges close by each other, and means for interconnecting the said members to form a rigid structure.
5. An electrostatic telephone, comprising a vibratory diaphragm, a capacity body cooperating with said diaphragm including a plurality of pressed sheet metal members, each formed with struck-up portions extending 10 in a direction away from the diaphragm for insuring the relative rigidity of the capacity body.
6. An electrostatic telephone comprising a diaphragm, a capacity body composed of a 15 plurality of sections opposed to said diaphragm, means for interconnecting said sections to form a relatively rigid structure, and means individual to each of said sections for clamping the opposed diaphragm area in respect to said sections respectively.
7. An electrostatic telephone, comprising a diaphragm, a capacity body composed of a 20 plurality of sections opposed to said diaphragm, said sections being formed with interlocking lug portions and recesses, and means for clamping said sections in respect to each other to form a relatively rigid structure.
8. An electrostatic telephone comprising a 25 diaphragm including conductive means, a capacity body composed of a plurality of sections respectively opposed to said diaphragm, and resilient means for clamping portions of said sections in respect to said diaphragm.
9. An electrostatic telephone comprising a 30 diaphragm including conductive means, a supporting frame member, a capacity body comprising a plurality of sections opposed to said diaphragm, and clamping means at the mid-portion of the diaphragm for inter- 35 connecting said members.
10. An electrostatic telephone construction comprising a cast frame member, a perforated metal capacity body having struck-up portions strengthening the same, and a vibratory diaphragm clamped in respect to said frame to extend over and to cooperate with 40 said capacity body.
11. An electrostatic telephone construction comprising a conductive vibratory dia- 45 phragm element, a plurality of relatively rigid capacity elements opposed to said diaphragm, a frame structure, and common means for clamping said diaphragm and said capacity members in respect to said frame 50 structure.
- In testimony whereof I have signed my name to this specification.
- RICHARD NAGEL.
